UNITED STATES PATENT OFFICE.

WILLIAM WERNER, OF MEXIA, TEXAS.

POST-ANCHORING DEVICE.

Application filed September 1, 1925. Serial No. 53,830.

My invention relates to an attaching means for securing a post to a concrete base. It is particularly applicable to the attachment of the posts employed in a standard rig for well 5 drilling and pumping operations.

In the building of standard rigs for well drilling and pumping operations, it is becoming more or less common to support the operating device upon a base of concrete, and 10 in so doing, the apparatus previously employed is modified to adapt it for attachment to a base of this nature.

It is an object of my invention to provide a substantial support between post and a concrete base which may be employed to quickly 15 attach and detach the post from the base, and will, at the same time, form a substantial and durable attachment.

It is also desired that the securing means 20 be adapted for use upon metal, wooden or cement structures, and be applicable to any type of post now in ordinary use.

Referring to the drawing herewith, Fig. 1 is a side elevation, partly in vertical section, 25 illustrating one embodiment of my invention. Fig. 2 is a horizontal section on the plane 2—2 of Fig. 1, the cement being removed from above the base plate. Fig. 3 is a side elevation of a post, the base being in vertical section, 30 and illustrating a second embodiment of the invention. Fig. 4 is a transverse section on the plane 4—4 of Fig. 3. Fig. 5 is a view similar to that shown in Fig. 1, illustrating a third embodiment of the invention, and Fig. 35 6 is another similar view, illustrating the adapting of the Fig. 5 modification to a tubular post. Like numerals of reference designate like parts in all the views.

In the building of standard rigs for operations on oil wells, there is ordinarily a Samson post and two jack posts. The Samson post furnishes a support for the walking beam, and the jack posts support the band wheel shaft. When these posts are secured 40 to a concrete base, I contemplate constructing the base to properly anchor and support the posts, whether it be the Samson post or the jack post. In the drawing it may be understood that either of these posts may be secured 45 to the base in the manner shown.

In the drawing, the concrete base is shown in broken section by the numeral 5. A socket 50 may be formed in this base to receive the post, and in such case, the socket may be made 55 practically square, as shown in Fig. 2. The socket 6, thus formed, may have a plate 7 at

the lower end thereof, supported upon cross rods 8, set in the cement at the level desired for the lower end of the post. These rods are preferably laid crosswise of each other, 60 as shown in dotted lines in Fig. 2, extending beyond the socket to reinforce the concrete at the point of support. A plurality of rods 9 are also set in the concrete, extending upwardly in the base to a point just below the 65 surface, where they are bent laterally at 10, to further reinforce the socket.

The post 11 may be of a section of pipe, as shown in Figs. 1 and 2, or of any other well known type of construction. The post is held rigidly on its seat within the socket, by means of anchor rods 12. There are preferably two of these rods, one on each side of the post, preferably on the forward and rear sides. Each rod extends from the base diagonally 75 upward through the post, and projects beyond the side of the post a sufficient distance to receive a washer 13 and a clamping nut 14 thereon, the end of the rod being threaded to receive the nut. The washer 13 is beveled or 80 inclined on its inner face to fit against the wall of the post in the manner shown in the drawing. The lower end of each brace rod 12, is secured within an eye-bolt 15, the lower end of which is shaped like the ordinary anchor 85 bolt, and imbedded in the concrete when the base is formed. The use of two opposite anchoring rods of this kind is found to secure the base rigidly in position so that it has no movement in any direction. It is particularly 90 efficient, and constitutes an important feature of the invention.

In Figs. 3 and 4, the same anchoring means is shown as adapted for use upon a solid post 16, which may be made of wood or concrete. 95 It is seated upon the base without the use of a socket particularly formed therefor. The base is reinforced, however, by means of longitudinal rods 17, having the ends thereof, at points each side of the post, turned downwardly for engagement in the concrete. The same anchor bolts 15 are employed, and the transverse rods 12 are extended diagonally 100 through the posts from opposite sides and secured in position, as previously described. The base and anchoring means thus provided is particularly efficient upon wooden posts, but may be employed upon any type of post of this nature.

In Figs. 5 and 6, an upwardly extending 110 boss 18 is formed upon the concrete base 5, said boss being preferably of cylindrical

shape, and reinforced around its outer sides, by steel rods 19 set into the cement and having their upper ends turned inwardly toward the center of the boss, as shown at 20. The 5 post 16' is formed with a socket in its base to fit over the boss thus formed, and is anchored to the base by means of the anchor bolts 15 and rods 12, as in the previous modification. The boss (as shown), fitting within the socket 10 in the base of the post, serves to resist lateral movement of the post, but it will be obvious that the rods 12, fitting closely within the openings through the post, and, clamped tightly to the post by means of the nuts 14, 15 will ordinarily be sufficient to hold the post in position without the assistance of the boss 18.

In Fig. 6, a boss 18', reinforced by rods 19', is formed as in the Fig. 5 embodiment, and 20 it is understood that the said boss may be formed of any desired size to fit within a tubular post 21, if desired. The base 5 in this modification has a series of parallel rods 17' along its upper surface to resist the wear 25 of the post upon the base and to make the support more substantial. In this modification, the anchoring rods 12 are dispensed with, and particularly when this construction is employed with the ordinary jack post having the 30 usual brace rods, such an attachment will be sufficient.

It will be noted that the attaching means shown and described may be connected with the base when the concrete is poured without 35 particular difficulty. Therefore, when posts are to be attached to the base, said attachment may be made with a minimum amount of adjustment and labor. This structure is particularly desirable, and has been found most 40 effective. The advantages will be apparent to those skilled in the art without further description.

What I claim as new and desire to protect by Letters Patent is:

45 1. A means for securing post to a concrete base comprising anchor bolts fixed in said base, said posts having diagonal openings in

a vertical plane therein extending through said posts on an approximately diametrical plane, anchor rods secured to said anchor 50 bolts and extending diagonally through said openings, and means to clamp said rods to said posts.

2. Means for securing posts to a concrete 55 base comprising anchor bolts secured in said base at opposite sides of said posts, anchor rods secured to said bolts and extending diagonally upward through openings in diametrically opposite sides of said posts, means on the ends of said anchor rods to 60 clamp the same to said posts, and additional means to resist lateral movement of said post relative to said base.

3. A means for securing a post to a concrete 65 base, comprising a boss formed on said base, a plurality of reinforcing rods around the periphery of said boss, said post having a socket therein to receive said boss, and additional means to secure said post upon said base, comprising anchoring rods secured to 70 said base and extending diagonally upward through said post so as to engage frictionally with said post adjacent the opposite ends of said rods.

4. In combination with a concrete base 75 having means thereon to receive a post, a post connected therewith, anchor bolts on said base, rods secured to said bolts and extended diagonally upward through a diametrical plane of said post to engage said post adjacent the two ends of said bolts, and means on said bolts to clamp them firmly to said base.

5. In combination with a post and a concrete 85 base, of means to secure said post to said base, comprising anchor bolts in said base closely adjacent said post, brace rods secured to said bolts and extending diagonally upward through said post, diametrically thereof, and means on said rods to clampingly 90 secure same to said post.

In testimony whereof I hereunto affix my signature this 13th day of August, A. D. 1925.

WILLIAM WERNER.
